UNITED STATES PATENT OFFICE.

JUSTUS A. TRAUT, OF NEW BRITAIN, CONNECTICUT.

BENCH-PLANE.

SPECIFICATION forming part of Letters Patent No. 291,815, dated January 8, 1884.

Application filed November 23, 1883. (No model.)

To all whom it may concern:

Be it known that I, JUSTUS A. TRAUT, a citizen of the United States, residing at New Britain, in the county of Hartford and State 5 of Connecticut, have invented certain new and useful Improvements in Bench-Planes, of which the following is a specification.

My invention relates to improvements in bench-planes; and the object of my improvement is to make a cheap and convenient form 10 of convertible "bull-nozed" and common hand plane. Such convertible planes have heretofore been made by a change in the position of the cutter. I attain this object by the 15 construction illustrated in the accompanying drawings, in which—

Figure 1 is a side elevation of my convertible plane. Fig. 2 is a partial plan view and section thereof on line $x x$ of Fig. 1. Fig. 3 20 is a side elevation of the same arranged for use as a bull-nozed plane.

The term "bull-nozed" is used to denote a plane in which the cutting-bit A extends practically to the forward end of the stock, to enable the plane to be used in planing up against a shoulder and in cramped places. Such planes 25 are well known in the art.

For the ordinary uses of a hand-plane, the forward end of the cutting-bit should be a little forward of the middle of the stock.

As shown in Figs. 1 and 2, my plane is so arranged for use as an ordinary block-plane. The general form of the stock B and the construction of the adjusting and holding mechanism may be of any ordinary character. I 35 form the forward end of the stock proper, B, with a vertical face or seat, c, upon which I secure the attachable and detachable stock-extension C by means of a screw, a. It is also

further secured by means of dowels b b, 40 secured to one part of the stock, or made integral therewith, and fitting into corresponding sockets in the other part, substantially as shown. After the extension C has been properly secured to the stock B, the bottom face of 45 the whole stock is planed or smoothed off, as shown in Fig. 1. The extension C then constitutes a part of the stock, and the plane is substantially the same for all the uses of the ordinary hand-plane as if the extension C were 50 made integral with the stock B. When it is desired to convert the instrument into a bull-nozed plane, it is only necessary to remove the fastening-screw a and the extension C, when 55 a well-balanced bull-nozed plane remains, as shown in Fig. 3.

By my improvement I produce a convertible bull-nozed and hand plane at a small expense, and in which both forms of plane are left in their ordinary characteristic and well-balanced form, and in which the cutter is not necessarily removed in changing from one form of plane to the other, and in which there is plenty of room to arrange the ordinary adjusting mechanism underneath and in the rear 65 of the cutter.

I claim as my invention—

The herein-described convertible plane, consisting of the stock B, adapted to receive and hold the cutting-bit, and provided with the attachable and detachable stock-extension C, substantially as described, and for the purpose 70 specified.

JUSTUS A. TRAUT.
